(57) **CLAIM**

The ornamental design for a loop-frame lectern with removable front panel, as shown and described.

DESCRIPTION

FIG. 1 is a perspective view of the lectern.

FIG. 2 is a rear view of the lectern.

FIG. 3 is a bottom view of the lectern.

FIG. 4 is a side view of the lectern.

FIG. 5 is a front view of the lectern; and,

FIG. 6 is a top view of the lectern.

The stipple pattern on the front panel in FIGS. 1, 2 and 5 indicates a flexible fabric material.
